UNITED STATES PATENT OFFICE.

ANDREW IZOLD, OF CAMP MEADE, MARYLAND.

TOILET CASE.

Application filed August 1, 1922. Serial No. 579,023.

To all whom it may concern:

Be it known that I, ANDREW IZOLD, a citizen of the United States of America, residing at Camp Meade, in the county of Anne Arundel and State of Maryland, have invented certain new and useful Improvements in Toilet Cases, of which the following is a specification.

This invention relates to certain new and useful improvements in toilet cases, particularly serviceable for travelers' use.

The primary object of the invention is to provide a generally simplified and improved toilet case embodying a container for toilet articles having a mirror exposed upon one side wall thereof and involving a pivoted or foldable prop at the opposite side whereby the device may be placed on a table or other support for convenient use of the mirror, while employing the various toilet articles carried in the container.

Another object of the invention is to provide the case or container with a comb or like receiving compartment of metal upon the rear side thereof having a struck out tongue adapted to receive the prop in folded or collapsed inoperative condition.

With the above general objects in view and others that will appear as the nature of the invention is better understood, the same consists of the novel form, combination and arrangement of parts hereinafter more fully described, shown in the accompanying drawing and claimed.

5 In the drawing, wherein like reference characters designate corresponding parts throughout the several views,

Figure 1 is a side elevational view of a toilet case constructed in accordance with the present invention shown operatively supported upon a table or the like,

Figure 2 is a view partly in vertical section and partly in rear elevation of the device shown in Fig. 1, with the prop in inoperative position.

Figure 3 is a horizontal sectional view taken upon line III—III of Fig. 1,

Figure 4 is an elevational view of a foldable brush adapted to be supplied with the toilet case, and

Figure 5 is a fragmentary elevational view of a foldable comb adapted to be received in the comb receiving compartment of the case.

Referring more in detail to the several views, the present invention embodies a case or container 5 per se which may have rounded ends and opposed flat front and rear or side walls as clearly shown as well as being divided by vertical partitions 6 into three compartments, the end compartment being rather or comparatively small, while the intermediate compartment is of such larger size as to conveniently accommodate a hair or other brush 7. One end 65 compartment is adapted to receive a tube of tooth paste or the like as at 8 while a foldable tooth brush having a double brush head as indicated at 9 may be provided in the other end compartment. These end compartments may be provided with suitable spring clips 10 adapted to engage the articles 8 and 9 to retain the same against accidental displacement therein.

The bottom of the case is enclosed by a 75 suitable bottom wall and each of the compartments has a pivoted closure or cover, the closures of the end compartments being indicated by the numeral 11 and the closure of the middle compartment being denoted by the numeral 12. As shown clearly in Fig. 2, the closures 11 are preferably disposed upon an inclination while clips or catches 13 may be provided to hold the closures 11 and 12 in closing position.

The front wall of the case 5 has a retaining flange 14 in which the margin of a mirror 15 is retained, and a U-shaped prop or support 16 is pivoted to the back wall of the case by hinging the ends of the 90 legs of said supports as at 17 to the upper part of the case. Suitable annular supporting spurs 18 may be fastened to the bottom wall of the case so that when the prop 16 is swung as shown in Fig. 1 the device will 95 be effectively supported in easel arrangement.

A somewhat pan-shaped metallic member 19 having marginal flanges 20 is attached to the back wall of the case substantially 100 centrally thereof, the means for attaching the same passing through the flanges 20 and the wall of the case, whereby the said wall of the case and the member 19 provide a vertical elongated pocket adapted for reception of a comb 21 or the like. The member 19 has a resilient tongue 22 stamped 105 from the lower end portion of the same

adapted to engage the intermediate or cross member 23 of the prop 16 when the latter is folded against the back of the case 5 in an inoperative position so as to be so held 5 when the device is not in use.

As shown in Fig. 4 the tooth brush 9 may consist of a pair of brushes with short shank portions pivotally connected together as at 24 so that the same may be conveniently 10 folded for reception within one of the end compartments of the case. In a like manner, the comb 21 may consist of a pair of sections one having a fine toothed construction and the other a coarse tooth construction and 15 pivotally connected as at 25 so as to be folded for reception within the pocket formed by the back wall of the case 5 and the metallic member 19. The folding of these sections is permitted as the same lie in different 20 planes, the section having the fine teeth being fixed upon one end of the pivot 25 while the other section is fixed upon the other end of said pivot.

The case 5 may be provided with numerous 25 openings 26 in the upper and lower ends of the end walls thereof for ventilating purposes, so as to insure against dampness upon the interior of the case and for the general ventilating purposes.

From the foregoing description it is to be 30 seen that the present invention embodies a neat, compact and complete toilet case which will give great service to travelers for assisting in making their toilet or for shaving 35 and the like.

It is believed that the construction and 40 manner of use as well as the advantages of the present invention will be readily understood and appreciated by those skilled in the art.

Minor changes may be made in the inven-

tion without departing from the spirit and scope thereof as claimed.

What is claimed as new is:—

1. A toilet case for travelers comprising a container having a plurality of compartments for the reception of different toilet articles and including a front wall having a mirror fastened exteriorly thereon, a substantially U-shaped prop pivotally attached to the back wall of the case by pivotal connection of the free ends of the legs of said support to the upper end of the back wall of the case, and a pan-shaped metallic pocket forming member attached to the exterior of the back wall of the case and including a struck-out resilient tongue adapted to engage the intermediate portion of the prop to hold the same in inoperative position against the back wall of the case.

2. A toilet case for travelers comprising a container having a plurality of compartments for the reception of different toilet articles and including a front wall having a mirror fastened exteriorly thereon, a substantially U-shaped prop pivotally attached to the back wall of the case by pivotal connection of the free ends of the legs of said support to the upper end of the back wall of the case, a pan-shaped metallic pocket forming 7 member attached to the exterior of the back wall of the case and including a struck-out resilient tongue adapted to engage the intermediate portion of the prop to hold the same in inoperative position against the back wall of the case, and supports comprising anti-slipping spurs secured to and projecting downwardly from the bottom of the case.

In testimony whereof I affix my signature. 8

ANDREW IZOLD.
